UNITED STATES PATENT OFFICE.

ANNIE E. ENGLAND, OF CALVERT, MARYLAND.

OVEN AND WARMING-CLOSET.

1,392,129.

Specification of Letters Patent. Patented Sept. 27, 1921.

Application filed December 8, 1920. Serial No. 429,122.

To all whom it may concern:

Be it known that I, ANNIE E. ENGLAND, a citizen of the United States, residing at Calvert, in the county of Cecil and State of Maryland, have invented certain new and useful Improvements in an Oven and Warming-Closet; and I do hereby declare the following to be a full, clear, and exact description of the invention, such as will enable others skilled in the art to which it appertains to make and use the same.

The object of the invention is to provide a comparatively simple and inexpensive structure which can be used interchangeably as an oven and as a warming closet in connection particularly with oil and gas stoves in the employment of which difficulty is ordinarily experienced in the fact that victuals after being cooked cannot be kept in a hot condition in the event of any delay in serving the same or when there is a necessity for postponing the service, without involving the risk of drying out or overcooking or burning the food and thus rendering it unpalatable or unfit for use, and the further difficulty that when several dishes are to be prepared, that is to say greater than can be accommodated upon the several burners with which the stove is provided, those which are first prepared cannot be kept in a proper condition while others are being prepared or cooked; and a further and incidental object of the invention is to provide means whereby the apparatus may be readily converted from one use to the other, that is to say from its use as an oven to that of a warming closet, or the reverse thereof, with the minimum of effort and loss of time upon the part of the operator and without involving any adjustment or rearrangement; and with these objects in view the invention consists in a construction and combination of parts of which a preferred embodiment is shown in the accompanying drawings, wherein

Figure 1 is a perspective view,

Fig. 2 is a rear view, and

Fig. 3 is a vertical sectional view of the device arranged for use as an oven.

Fig. 4 is a perspective view, and

Fig. 5 is a vertical sectional view of the device arranged for use as a warming closet.

Figs. 6 and 7 are detail views in perspective of the interchangeable members by the alternation of which the device is converted from an oven to a warming closet.

The apparatus consists essentially of a casing 10, which obviously may be of any preferred or desired dimensions and shape to suit the purposes of the user and the size of the stove or the number of burners with which the stove is provided, or which it is desired shall be used in connection with the device, on the front of which is arranged a door 11 giving access to the interior which is provided with terminal ledges 12 for supporting shelves or trays 13.

At the opposite wall of the casing which for convenience may be termed the rear side is arranged a supplemental door 14, preferably hinged at the end, instead of at the lower edge as is the oven door 11, said supplemental door covering an opening which is formed in the upper portion of the casing, and beneath which is provided an opening 15 adapted to receive the interchangeable box and wall members 16 and 17, by the alternate use of which the structure is converted into either an oven suitable for baking, roasting and the like, and a warming closet in which food may be kept at the desired temperature for an indefinite length of time. The box member 16 consists of an upper wall 18, a front wall 19 and end walls 20, the top and end walls being laterally flanged 21 as indicated at 21 to bear against the exterior surface of the casing, and the rear of said box being open, so that when this member is in use and the structure is arranged upon the stove plate, the burners, while furnishing heat to the warming closet, which consists of the portion of the interior of the casing above the plane of the upper wall of said box, to keep it at a proper temperature, at the same time are accessible for use in cooking or preparing other articles of food.

For example a kettle of water may be arranged over one of the burners, the other being out of use, or other articles as above indicated may be cooked on both or all of the burners which can be reached through the opening at the rear of the box; or by keeping one of the burners in operation with the flame turned down very low, a sufficient heat will be conveyed to the warming closet to maintain the proper temperature therein, and articles or dishes may be introduced into or removed from the compartment used under these conditions as a warming closet and located above the plane of the upper wall of the box 16, either by means of the main oven door 11 or the supplemental door 14. It

will be noted that the bottom of the box member 16 is completely open.

The alternative or interchangeable member 17 consists of a wall plate or section 5 which is adapted to be fitted to the opening 15 in the rear wall of the casing and is provided with turn buttons 22 or equivalent fastening means for engagement with the edges of the wall opening to secure said plate 10 or section in position to complete the oven when it is desired to use the latter for baking or roasting. In this connection it is preferred to use a tray shelf 23 consisting of a rack adapted to be supported upon the 15 lowermost ledges of the oven wall and having impendent relation therewith a deflector or baffle plate 24 terminally supported from the rack and adapted to serve as a means of distributing the heat as it rises from the 20 burner so that a uniform temperature may be maintained in the oven.

Also as will be understood ventilating openings 25 may be provided in the end walls or in any other convenient position in 25 the casing, and peep holes 26 may be provided in the front wall and may be fitted with isinglass or other light penetrable mediums or panels to enable the operator to observe the condition of the interior of the 30 oven and the state of the burners and the like.

The casing 10 is provided with handles 10^a. The oven door 11 is provided with sight openings 11^a covered by transparent panels 35 11^b, and the warming closet door 14 is provided with a ventilator 14^a. A handle 21^a is secured to the box member 16, and the oven door 11 is removably secured in closed position by turn buttons 11^c. The casing 10 is 40 provided with a bottom front flange 10^a, bottom end flanges 10^b and rear side flanges 10^c. The member 16 coöperates with these flanges and with the side and end walls of the casing to provide passages 10^d which are 45 closed except at their upper ends where they communicate with the compartment above and formed by the top wall of the member.

Having thus described the invention, what I claim is:—

50 1. A convertible oven and warming closet having interior shelves and a door for giving access to the interior, and having one of its sides cut away near the bottom to form an opening, and interchangeable members for closing said opening, one of said members

consisting of an interiorly accessible box for partitioning the interior of the casing.

2. A convertible oven and warming closet 60 interiorly divided by a horizontal partition to form upper and lower compartments of which the latter is bottomless and is exposed interiorly through an opening in the side of the closet, and end walls on said partition spaced from the end walls of the closet.

3. A convertible oven and warming closet 65 interiorly divided by a horizontal partition to form an upper and lower compartment of which the latter is bottomless and is exposed interiorly through an opening in the side wall of the closet and a side wall and end 70 walls on said partition spaced from one side wall and the end walls of the closet to form passages in communication with the upper compartment.

4. A convertible oven and warming closet 75 having an opening in its bottom and an opening in one of its sides near its bottom, a removable member positioned in the closet and having an open bottom and side adjustable said openings in the closet, and a member 80 for closing said side opening of the closet after the removal of said first member.

5. A convertible oven and warming closet having an opening in its bottom and an opening in one of its sides near its bottom, 85 bottom and side flanges formed on the closet about said openings, and a member removably positioned within the closet and having top and front and end walls coöperating with said flanges and the adjacent walls of 90 the closet to provide passages communicating with the closet above the top wall of said member and having their lower ends closed.

6. A convertible oven and warming closet having an opening in its bottom and an 95 opening in one of its sides near its bottom, and a removable member positioned in the closet and having a top and a front and end walls coöperating with the closet to provide an upper compartment and a lower compartment 100 and passages about the lower compartment communicating with the upper compartment, the lower compartment being open at one side and the bottom.

In testimony whereof I affix my signature 105 in presence of two witnesses.

ANNIE E. ENGLAND.
